ATTORNEYS.

UNITED STATES PATENT OFFICE.

CHARLES LEXOW, OF ROSEBANK, NEW YORK.

DESIGN FOR TRIMMING.

SPECIFICATION forming part of Design No. 21,830, dated September 6, 1892.

Application filed June 21, 1892. Serial No. 437,524. Term of patent 3½ years.

To all whom it may concern:

Be it known that I, CHARLES LEXOW, of Rosebank, in the county of Richmond and State of New York, have invented and produced a new and original Design for Trimmings, of which the following is a specification, reference being had to the accompanying drawings, in which—

Figure 1 is a perspective view of a trimming, showing my design. Fig. 2 is a cross-section of the same.

The leading feature of my design consists of loops A and sets of straight lines B, all radiating from a common center on a band,

rope, or braid-like figure C. As shown in the drawings, the loops and lines are approximately the same length, so as to produce a rib semicircular in cross-section or circular effect. The loops are arranged alternately with the sets of lines.

20

I claim—

The design for trimmings, as herein shown and described.

CHARLES LEXOW.
